RAYMOND L. JEWELL, OF MILLCREEK TOWNSHIP, ERIE COUNTY, PENNSYLVANIA,
ASSIGNOR TO AMERICAN STERILIZER COMPANY, OF ERIE, PENNSYLVANIA, A COR-
PORATION OF PENNSYLVANIA

STEAM-GENERATOR-CONTROLLING MECHANISM

Application filed November 25, 1925. Serial No. 71,482.

This invention is designed to control steam generators, particularly such generators as may be used in such connections as sterilizers. With such devices it is desirable to normally control the generator through a pressure regulator and to completely cut off the heat from the generator upon an abnormally low water level through a thermally controlled device. It is also desirable to have a minimum shut-off under the pressure device which will deliver just an amount of heat necessary to take care of the normal condensation under working conditions. Features and details of the invention will appear more fully from the specification and claims.

an arm 21 which engages a shoulder 22 on a valve stem 28. A valve head 24 is mounted on the valve stem. A spring 25 is arranged under the bonnet against the valve head and tends to close the valve when released. The valve operates on a seat 26 arranged on a web 27 in the valve body. The lever 19^a is provided with a handle 23 by means of which the trigger mechanism and levers may be reset. 55

Gas is delivered to the valve body through a supply pipe 29, passes through the valve seat and web and is discharged through a discharge opening 30 to the burner 2.

A pressure valve 31 operates on a seat 32 on the underside of the web. This valve has a hollow stem 33 which is guided in a diaphragm fitting 34. A cap 35 is arranged on the diaphragm fitting 34 and a stem 36 is screw-threaded into the cap 35 and extends 70 upwardly into the hollow stem 33. The stem is provided with a head 37 and a spring 38 is arranged between the head 37 and a cap 39 arranged in the end of the hollow stem 33. A diaphragm 40 is clamped on the end of the stem by means of the cap 39 and the diaphragm is secured between the diaphragm fitting 34 and a cap 35 by screws 35^a. The cap is connected with the generator chamber by a pipe 41 so that the underside of the diaphragm is subjected to generator pressure and this is opposed by a spring 38. 75 80

A bypass 42 is arranged between the seat 32 and the seat 26 so that when the valve 24 is open and the valve 31 is closed gas will pass through the bypass but when the valve 24 is closed the gas is cut off. The bypass 42 may be adjusted by a valve 43 which has a screw-threaded stem with a slotted end 44. The opening outside the valve 43 is closed by a plug 45 so as to make it gas tight. 85 90

The operation of the mechanism is as follows: When the generator is operating normally and steam is first turned into the sterilizer this reduces the pressure so that the pressure actuated valve 31 is opened and there is a full flow of gas to supply the emergency steam. As soon as the sterilizer is filled and begins to operate normally pressure builds up and closes the valve 31 and gas is then delivered.

ered through the bypass just sufficient to take care of the condensation. Should for any reason there be a failure of water and the level of liquid should fall low enough to empty the thermal element the gas operating on the thermal tube so expands it as to operate the trigger mechanism and release the valve 24, thus closing off all the gas and it remains closed until re-opened by the operator.

10 In the drawing, Fig. 1, the water level is shown as having reached the level of the top of the elbow and the thermal unit is shown as having been emptied through the steaming of the gas jet. With this condition the thermal element is expanded under the heat and within a very short interval the gas valve will be closed.

What I claim as new is:—

1. In a steam generator controlling mechanism, the combination of a generator chamber; an elbow having an arm extending upwardly into the chamber and a horizontal arm without the chamber; a thermally sensitive tube extending from the horizontal arm; 20 a burner under the thermal tube; a valve controlling the burner and responsive to temperature rises in the tube; and a tube venting the thermal tube in the chamber extending from a point remote from the elbow to above 25 the upper end of the elbow.

2. In a steam generator controlling mechanism, the combination of a generator chamber; an elbow having an arm extending upwardly into the chamber and a horizontal 30 arm without the chamber; a thermally sensitive tube extending from the horizontal arm; a burner under the thermal tube; a valve controlling the burner and responsive to temperature rises in the tube; and a tube venting the 35 thermal tube in the chamber through the elbow; said vent tube being arranged in the thermal tube and extending from a point in the horizontal arm remote from the elbow to a point in the chamber above the top of the 40 elbow.

3. In a steam generator controlling mechanism, the combination of a steam generating chamber; a gas burner heating said chamber; a thermal element subjected to the liquid 45 of the chamber and the heat of a gas burner; a valve controlling the burner and responsive to the thermal element with an increase of temperature; a valve seat for the thermally controlled valve; an opposing seat; a pressure responsive valve operating on the opposing seat; and a pressure device responsive to generator pressure controlling the pressure responsive valve.

4. In a steam generator controlling mechanism, the combination of a steam generating chamber; a gas burner heating said chamber; a thermal element subjected to the liquid of the chamber and the heat of the gas burner; a valve controlling the burner and responsive to the thermal element with an in-

crease of temperature; a valve seat for the thermally controlled valve; an opposing seat; a pressure responsive valve operating on the opposing seat; and a pressure device responsive to generator pressure controlling the pressure responsive valve comprising a diaphragm, a cylindrical stem on the pressure controlled valve secured to the diaphragm, a headed pin extending into the stem, and a spring in the stem between the head on the pin and the diaphragm.

5. In a steam generator controlling mechanism, the combination of a steam generating chamber; a gas burner heating said chamber; a thermal element subjected to the liquid of the chamber and the heat of the gas burner; a valve controlling the burner and responsive to the thermal element with an increase of temperature; a valve seat for the thermally controlled valve; an opposing seat; a pressure responsive valve operating on the opposing seat; and a pressure device responsive to generator pressure controlling the pressure responsive valve comprising a diaphragm, a cylindrical stem on the pressure controlled valve secured to the diaphragm, a headed pin extending into the stem, a spring in the stem between the head on the pin and the diaphragm, and means for adjusting the pin.

6. In a steam generator controlling mechanism, the combination of a steam generating chamber; a gas burner heating said chamber; a thermal element subjected to the liquid of the chamber and the heat of a gas burner; a valve controlling the burner and responsive to a change of temperature in the thermal element; a valve seat for the thermally controlled valve; an opposing seat; a pressure responsive valve operating on the opposing seat; a pressure device responsive to generator pressure controlling the pressure responsive valve; and a bypass between the opposing seats.

7. In a steam generator controlling mechanism, the combination of a generator chamber; a gas burner; a gas supply passage leading to the burner; a pressure device sensitive to chamber pressure closing and opening said passage in response to pressure; a thermal element exposed to the heat of the burner; a trip device released by the thermal element cutting off the gas burner upon an increase of temperature in the thermal element; and a bypass around the pressure device, the trip device being more remote from the burner than the bypass whereby the bypass is closed as the trip device is operated.

8. In a steam generator controlling mechanism, the combination of a generator chamber; a gas burner; a pressure device sensitive to chamber pressure controlling said gas burner; a thermal element exposed to the heat of the burner and subjected to the liquid of the chamber; a valve controlled by the

thermal element cutting off the gas burner in response to said control in the absence of a liquid in the chamber; a bypass around the pressure device; and means for adjusting the bypass, the valve being more remote from the burner than the bypass whereby the bypass is closed as the valve is closed.

In testimony whereof I have hereunto set my hand.
